CLAIM

The ornamental design for a spokes, as shown and described.

DESCRIPTION

FIG. 1 is a right side perspective view of spokes showing our new design, it being understood that the pattern repeats uniformly throughout the circumference of the tread;

FIG. 2 is a second right side perspective view thereof;

FIG. 3 is a front elevational view thereof;

FIG. 4 is a rear elevational view thereof; and,

FIG. 5 is a right side elevational view thereof; the top, bottom and left side elevational views being a mirror image thereof.

In the drawings, the broken lines showing of the tire tread, inner bead and hub depict environmental subject matter and form no part of the claimed design.

1 Claim, 5 Drawing Sheets(56)
